BATHING SUIT

Sam Annis, New York, N. Y.

Application January 8, 1951, Serial No. 13,703

Term of patent 3½ years

(Cl. D3—17)

To all whom it may concern:

Be it known that I, Sam Annis, a citizen of the United States, residing at New York city, in the county and State of New York, have invented a new, original, and ornamental Design for a Bathing Suit, of which the following is a specification, reference being had to the accompanying drawing, forming a part thereof.

Fig. 1 is a front view of a bathing suit, showing my new design.

Fig. 2 is a back view thereof.

Fig. 3 is a side view thereof.

I claim:

The ornamental design for a bathing suit, substantially as shown.

SAM ANNIS.
